(No Model.)

F. B. SMITH.

MATCH BOX.

No. 391,489.

Patented Oct. 23, 1888.

UNITED STATES PATENT OFFICE.

FRANK B. SMITH, OF NORTH SPRINGFIELD, MISSOURI, ASSIGNOR OF ONE-FOURTH TO EDWIN B. LOVELAND, OF SAME PLACE.

MATCH-BOX.

SPECIFICATION forming part of Letters Patent No. 391,489, dated October 23, 1888.

Application filed March 18, 1887. Serial No. 231,344. (No model.)

To all whom it may concern:

Be it known that I, FRANK B. SMITH, of North Springfield, in the county of Greene and State of Missouri, have invented certain new and useful Improvements in Match-Boxes; and I do hereby declare the following to be a full, clear, and exact description of the invention, such as will enable others skilled in the art to which it appertains to make and use the same.

My invention relates to an improvement in match-boxes.

The object is to provide a match-box of light and inexpensive material, which may be easily manufactured and shipped, and one which may be quickly put together for use.

A further object is to provide a match-box more convenient for the consumer and less expensive to manufacture, which may be hung in a convenient position with the ends of the matches exposed in position to be easily removed.

A further object is to provide the box with means whereby the matches are easily ignited when removed from the box, and also with a surface which may be used for advertising purposes, lessening the cost to the match-manufacturer, and affording a suitable space in addition for the brand of the matches to be always exposed to view of the consumer.

With these ends in view my invention consists in certain features of construction and combinations of parts, as will be hereinafter fully described, and pointed out in the claims.

In the accompanying drawings, Figure 1 is a view of one form of blank. Fig. 2 is a view in perspective of the box suspended in position for use. Fig. 3 is a side elevation.

A represents the portion of the blank which forms the front of the box, and B the lower end adapted to be bent along the line indicated by dotted line b to form the bottom. The dotted lines a a' at the sides indicate the bend in the blank to form the sides C, while preferably parallel with dotted lines a a' are the dotted lines c c', which mark the juncture between the sides C and sections D D', forming the back. The back is formed of a pair of approximately equal sections or half-sections, the entire width of the two when fast-

ened together at the edges by a slight lap being the same or approximately the same as the width of the front A, and the back D D' and front A are in such relative positions to each other that the latter is below the former, so that the lower edges, d, of the sides C slant or are oblique. When put together with the sections D D'lapping slightly, the back is stiffened through the middle f and the bottom slants at an angle of about forty-five degrees, the triangular flaps g being fastened to the inside of the sides and the lower ends, E, of the back sections, D D', lapping over the bottom B. The upper ends of the back sections, D D', terminate in the flaps F, which are sanded on the inside for lighting matches when scratched thereon. An eyelet, h, is formed in the flap through the lapped portion, by means of which the box is hung on the wall or in other convenient places. To close the box, the end of the flap F is simply placed in the slit i in the upper edge of the front A; or the flaps may be slipped inside the front edge of the box and no slit made. By forming the eyelet h in the lapped portion of the flap additional strength is given to it. The front and sides of the box are plainly visible when the box is suspended, and hence I desire to utilize them as a desirable means for advertising.

As the boxes are constructed in the blank, large numbers may be shipped in comparatively small space, and even when filled with matches the formation of the box is such that comparatively little space is occupied by each one. Importance is attached to the fact that the boxes being provided with means for hanging vertically, the match-heads being turned downward, there is no danger of their becoming accidentally lighted by the box being thrown around carelessly, and, owing to the slanting formation of the bottom, the matches rest in the box in successive rows, those at the back above those at the front, so that the matches are very conveniently removed and without touching their heads, except as they are drawn across the face of the sanded flap.

It is evident that slight changes in the formation of the box might be resorted to, such as different sizes and styles, and that other slight

changes might be made without departing from the spirit and scope of my invention; hence I do not wish to limit myself to the particular construction herein set forth; but,

5 Having fully described my invention, what I claim as new, and desire to secure by Letters Patent, is—

10 1. A match-box formed of a single blank cut to form a central portion for the front wall, portions for the side walls, the bottom, flaps completing the bottom, and overlapping portions for the back having a suspending-eyelet in the overlapping portion, substantially as set forth.

15 2. A match-box formed of a single blank cut to form a central portion for the front wall, portions for the side wall having inclined upper and lower edges, the bottom, flaps com-

pleting the bottom, and overlapping portions for the back having a suspending-eyelet in 20 the overlapping portion, substantially as set forth.

3. A match-box having the front, sides, bottom, and back formed substantially as described, the sections of the back adapted to 25 lap each other and the covering-flap formed thereby being sanded on its inner surface and provided with an eyelet, substantially as set forth.

In testimony whereof I have signed this 30 specification in the presence of two subscribing witnesses.

FRANK B. SMITH.
